UNITED STATES PATENT OFFICE.

THOMAS FRANK CHEANEY, OF FORT LAUDERDALE, FLORIDA.

PRINTING PROJECTOR.

Application filed May 4, 1925. Serial No. 27,824.

To all whom it may concern:

Be it known that I, THOMAS FRANK CHEANEY, a citizen of the United States, residing at Fort Lauderdale, in the county of 5 Broward and State of Florida, have invented certain new and useful Improvements in a Printing Projector, of which the following is a specification.

The present invention relates to what I 10 term a printing projector and relates to the art of reproduction by employing the principle of photography.

The invention contemplates the provision of a casing having means therein for supporting an object and a source of illumination directed onto the object so that the image thereof may be projected through a lens located between the source of illumination so as to be directed onto a sensitized 20 sheet. The image may be projected directly onto the sensitized sheet if a negative is to be made, but if a positive reproduction is desired, a mirror is used so that the projection is reflected to a shelf supported to 25 one side of the casing.

An important object of the invention is to provide a printing projector of this nature which is exceedingly simple in its construction, capable of being operated easily 30 and quickly, one which is inexpensive to manufacture and maintain, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts 40 as will be hereinafter more fully described and claimed.

In the drawing:—

Figure 1 is a side elevation of the invention embodying the principle thereof showing the hinged side open,

Figure 2 is an end elevation thereof, and

Figure 3 is a detail perspective of an attachment.

Referring to the drawing in detail, it is to 50 be noted that I have illustrated what might be considered as the mere essentials of the invention in order to illustrate an operative, useful, and simple example of the invention. The letter C indicates generally a casing, 55 which includes a bottom 5, a pair of ends 6, a pair of sides 7 and 8, and a top 9. The side

8 is hingedly mounted as at 10 so as to afford easy and ready access to the interior of the casing. A plurality of vertically spaced cleats 11 are mounted on the inner 60 surfaces of the ends 6 and afford means for holding a panel 12 in different vertical positions. This panel 12 is provided with spring clips 13, or any other suitable means for supporting on the panel an object 14 65 which may be in the form of a printed sheet, a photograph, or any other object which it is desired to reproduce. In the present example of the invention, two sources of illumination 15 are illustrated as depending 70 from the top 9 downwardly into the casing, and preferably consists of ordinary electric bulbs with shades and reflectors disposed thereabout for directing the rays of light downwardly onto the object 14. A lens 16 75 is disposed in the top 9 between the two sources of illumination 15, so that the image of the object 14 will be reflected therethrough.

As is well known, the object will be inverted when projected through the lens 16. I, therefore, provide a standard 17 rising from the top 9 and having slidable thereon a bracket 18 which includes the sleeve 19 that receives the standard 17. A spring 20 85 projects from the bracket 18 and frictionally engages the standard 17 in order that the bracket may be placed in different adjusted positions on the standards after which the set screw 21 may be tightened. A 90 mirror 22 is pivotally mounted on the bracket 18 in any suitable manner and receives the image from the lens 16 as is indicated to advantage in Figure 2. Arms 23 are fixed to the side 7 being suitably 95 braced as at 24, and extend upwardly and slant away from the side 7. Between the extremities of the arms 23 there is pivotally supported a shelf 25, on which a sensitized sheet is disposed so that the image from the mirror 22 may be directed thereon. The 100 reproduction which will be formed on the sensitized sheet will be a positive reproduction. At times, of course, it is desirable to make negative reproductions. This may be done 105 by removing the mirror 22. Brackets 27 are mounted on the exterior surfaces of the ends 6 in vertical alignment and have set screws. A frame 28 with a plate glass panel 29 therein is supported on rods 30 110 which are receivable in the brackets 27 so that this plate glass panel may be held at

- different adjusted distances above the top 9. By placing the sensitized sheet thereon, the image will be projected directly thereon and a negative reproduction will be made.
- 5 The important idea contained in this printing projector is the provision of a projector which prints through the use of indirect lights. It is apparent that numerous refinements may be incorporated with 10 the essentials which I have described in order that the exposure may be automatically controlled, and in order that the sensitized sheets may be quickly replaced for quantity reproduction. I therefore wish 15 it understood that numerous changes in the details of construction, in the sizes, and in the combination and arrangement of parts may be resorted to without departing from the spirit or scope of the invention as hereinafter claimed or sacrificing any of its 20 advantages.
- Having thus described the invention, what I claim as new and desire to secure by Letters Patent is:—
- 25 1. A printing projector of the class described, including a casing formed from a bottom, ends, sides slanting upwardly toward each other, and a top, cleats on the ends interiorly of the casing, a panel supported in said cleats, sources of illumination suspended from the top in the casing for directing rays of light onto the object on the panel, a lens disposed in the top between the sources of illumination to receive 30 the image from the object, and project it outwardly of the casing, a mirror adjustably mounted on the casing for receiving the image from the lens, and a shelf adjustably supported to the side of the casing for 35 holding a sensitized sheet to receive the image from the mirror.
4. A printing projector of the character described including a casing formed from a bottom, ends, a pair of sides slanting upwardly toward each other and a top, an object supporting panel adjustably supported between the ends in the casing, a source of illumination supported by the top of the casing for directing rays of light onto 40 the object mounted on the panel, a lens disposed in the top for receiving the reflected rays from the object and projecting them exteriorly of the casing, and a sensitized sheet supporting means disposed exteriorly of the casing for receiving the image projected through the lens.
2. A printing projector of the class described, including a casing formed from a bottom, ends, sides slanting upwardly toward each other, and a top, cleats on the ends interiorly of the casing, a panel supported in said cleats, sources of illumination 45 50 55 60 65 70 75 80 85
3. A printing projector of the class described, including a casing formed from a bottom, ends, sides slanting upwardly toward each other, and a top, cleats on the ends interiorly of the casing, a panel supported in said cleats, sources of illumination suspended from the top in the casing for directing rays of light onto the object on the panel, a lens disposed in the top between the sources of illumination to receive the image from the object, and project it outwardly of the casing, a mirror adjustably mounted on the casing for receiving the image from the lens, and a shelf adjustably supported to the side of the casing for holding a sensitized sheet to receive the image from the mirror.
4. A printing projector of the character described including a casing formed from a bottom, ends, a pair of sides slanting upwardly toward each other and a top, an object supporting panel adjustably supported between the ends in the casing, a source of illumination supported by the top of the casing for directing rays of light onto the object mounted on the panel, a lens disposed in the top for receiving the reflected rays from the object and projecting them exteriorly of the casing, and a sensitized sheet supporting means disposed exteriorly of the casing for receiving the image projected through the lens.

In testimony whereof I affix my signature.
THOMAS FRANK CHEANEY.
